INTERCHANGEABLE ELECTRIC LIGHT
FIXTURE HANGER AND SOCKETVernon V. Veysey and Harvey R. Andersen,
Neenah, Wis.

Application March 27, 1933, Serial No. 662,880

12 Claims. (Cl. 247—20)

This invention relates to improvements in combination electrical outlets and hangers for lighting fixtures.

It is the primary object of the invention to provide a novel and improved organization of electrical outlet and hanger so designed as to facilitate the mounting and dismounting of electrical fixtures, and preferably so contrived that the parts which serve to provide the current path from the house wiring to the fixture also serve as a fixture mounting means, such parts having mechanism insulated to facilitate the manipulation of the parts for their engagement and disengagement in the mounting and dismounting of the fixture.

It is a further object of the invention to promote safety by protecting electricians, plasterers and painters, and other persons having need to manipulate electric fixtures from contact with bare wires; and to eliminate all need for the connection and manipulation of ordinary wires in the hanging and removal of fixtures.

One form of the invention is illustrated in the accompanying drawing wherein:

25 Figure 1 is a longitudinal section through a device embodying the invention showing a detachable plug portion partially inserted into the mounting socket adapted to receive it.

Figure 2 is a view in longitudinal section similar to Figure 1 showing the plug portion anchored within the mounting socket, the electrical connection between the parts being established by the mounting means.

35 Figure 3 is a detail view of a portion of the mounting socket in transverse section.

Figure 4 is a detail in perspective of the removable plug portion of the device.

40 Figure 5 is a view in section of a dummy plug which may be used to close the socket where the outlet is intended to be plastered over temporarily.

Like parts are identified by the same reference characters throughout the several views.

45 The usual outlet or junction box 6 is secured to the support 7 in the usual manner. I have shown it to be connected with the conventional "BX" cable or sheath 8 through which the current supply wires 9 and 10 are led to the interior of box 6.

50 Fittings 11 and 12, such as are used in the mounting of an ordinary receptacle in an outlet box, are employed to support in box 6 a special receptacle 15 which is preferably made of porcelain or some other suitable insulating material. The receptacle has a central opening at 16 which tapers from a large cross section to a small cross section toward the open side of the box 6.

55 Applied to the converging opposite faces of opening 16 are contact plates 17 and 18 to which the wires 9 and 10 are connected by means of terminal screws 19 and 20 respectively. The

cover 21 screwed to fittings 11 and 12 is applied to the lath 22 and plaster 23 to close the front of the box 6 except for an aperture at 24 in registry with the opening 16 of the receptacle.

The chain shown at 25 in Fig. 2 may be taken to represent any conventional fixture. As is usual, where a chain-supported fixture is used, the chain engages with the hook portion 26 of a special nut 27. In accordance with the present invention, the nut is suspended upon the lower end of a rod 28 which is swiveled in a block of insulating material shown at 29, and is screw threaded at its upper end for interaction with a wedge 30, likewise formed of insulating material.

Projecting upwardly from the insulating block 29 are the combined supports and contacts 35, preferably provided at their upper ends by thickened pad portions 36 made by folding the contact plates upon themselves and filling with solder or the like the eye thus formed. When the contact and supporting elements 35 are parallel to each other as shown in Fig. 1, they are readily insertable into and removable from the opening 16 at the receptacle 15. A rib at 37 on the block 29 registers with a groove at 38 and receptacle to 25 ensure, where desired, that the contact elements 35 will register with the proper contact plates 17 and 18, so that the polarity of the current received by the plates may be known.

If the plug assembly is fully inserted in the receptacle as shown in Fig. 2, and the rod 28 is turned to screw the wedge 30 downwardly between the pad elements 36 at the upper end of the contact and supporting springs or members 35, the said contact and supporting spring 35 members will be expanded in the tapered opening 16 as shown in Fig. 2 and thereby will be anchored securely against withdrawal within the strength of the material used. Any desired object may now be suspended upon the rod 28, 40 which is adequately able to support any conventional fixture connected thereto by means of the hook at 26. The fixture wires 38 and 39 are connected by means of terminal screws 49 with the combined contact and supporting members 35.

These wires are preferably confined within a tubular housing 41 and a conventional finishing "bell" 42. A washer at 43, duly notched to pass the wires 38 and 39, is engaged by the nut 27 50 to support the tubular housing 41 and the bell 42.

In case it is desired to conceal the fixture outlet beneath plaster, as is sometimes the case, the opening 16 in the receptacle may be temporarily closed by means of a plate 45 applied to 55 the bottom of the receptacle and there firmly held by means of dummy contacts 35' carried by insulating block 46 and expanded by means of a wedge 30 operated by a screw headed rod 28'.

It will be understood that the device herein 60

- specifically described is but one of many forms which the invention may take to support any kind of an electrical fixture which requires both electrical connection and mechanical support.
5. The receptacle and plug fitting herewith disclosed may also be used wherever it is desired to continue an electrical circuit through means which provides a mechanical as well as an electrical connection.
10. As applied to electric lighting fixtures, the apparatus enables the most inexperienced operator to mount or dismount an electrical fixture with no danger to himself. Thus it is not only of value to electricians in the ordinary installation 15 of such fixtures, but is also of value to plasterers, painters and others who may have occasion to remove a lighting fixture to facilitate their work. Also, the invention enables the ordinary householder to interchange his electrical fixtures without asking for the services of an electrician.
- We claim:
1. A combined fixture hanger and outlet receptacle comprising the combination with a pair of contacts and an apertured receptacle providing insulation and mounting for said contacts, and affording access thereto, of a fixture support comprising insulating means and conductors mounted thereon and individually engageable with the respective contacts of the receptacle and 30 adapted for simultaneous manipulation for mechanical connection with the respective contacts to receive support and also to receive electrical energy therefrom, and means for mechanically engaging said conductors positively with the respective contacts.
2. The combination with a pair of contacts and a recessed receptacle providing insulation and comprising a supporting part and affording access to said contact, of a plug device comprising a 40 supported part and providing a pair of laterally movable prongs complementary to the respective contacts, and mechanical and positive means for moving said prongs laterally for the mechanical inter-engagement of said prongs with said contacts to provide a releasable mechanical and electrical connection therebetween.
3. The combination with a receptacle provided with spaced contacts, of a fitting provided with 50 prongs complementary to the contacts, and means holding said prongs at points spaced differently from the spacing of the contacts, together with manually operable means for the mechanical manipulation of said prongs with respect to each other and said contacts in a direction to engage said prongs mechanically and electrically with the respective contacts, whereby to secure said fitting to said receptacle in electrically operative relation.
60. 4. The combination with a receptacle member and a fitting member arranged for mechanical and electrical connection, of spaced contacts carried by the respective members, means providing suitable insulation for the contacts, and mechanically operable positive means for moving a plurality of contacts simultaneously in a lateral direction for engaging the contacts of one of said members with the contacts of the other in mechanical and electrical connection.
65. 5. The combination with a receptacle having an internal recess leading to a reduced opening, of contacts carried by said receptacle at different sides of said opening, a fitting including prongs receivable through said opening, and means for

mechanically expanding said prongs positively into engagement with said contacts for mechanical and electrical connection therewith, whereby said prongs are secured in said receptacle against the possibility of withdrawal save by manipulation of said means. 5

6. The combination with an apertured receptacle having an internal recess with walls converging toward the aperture, mutually insulated contacts disposed on different walls, a fitting comprising a fixture support and provided with mutually insulated contact prongs receivable through said aperture, positively acting means for mechanically expanding said prongs to receive mechanical support from said walls, said 15 prongs having portions engageable with said contacts when so expanded. 10

7. The combination with a pair of outwardly converging contacts and a receptacle providing insulated support therefor, of a fixture carrying 20 fitting provided with mutually insulated prongs and a wedge disposed between said prongs and provided with means for its adjustment in a direction to expand said prongs into mechanical and electrical connection with said contacts. 25

8. The combination with an outlet fitting comprising an apertured dielectric block, the aperture being outwardly tapered to a reduced cross section, of contacts carried by opposing converging portions of said block adjacent the aperture 30 therein, a fitting comprising insulating means, and spaced prongs carried thereby and receivable into the aperture of said block, an adjusting rod movable in said means, and a wedge connected with said rod for manipulation thereby and disposed between said prongs, said wedge being adapted to expand said prongs into mechanical and electrical connection with said contacts. 35

9. An outlet receptacle comprising a support provided with a plug receiving aperture having 40 an inlet, in combination with solidly mounted and relatively non-yielding supporting and electrical contacts converging toward each other toward said inlet and provided with mutually insulated mounting upon said support at opposite sides of 45 said aperture.

10. In a device of the character described, a plug fitting comprising a pair of conducting prongs having movable free end portions, of means providing insulated support for said 50 prongs, and a manually operable actuator extending through said means for the manipulation of the free end portions of said prongs and including mechanism acting positively on the free end portions of the prongs. 55

11. In a device of the character described, a plug fitting comprising a dielectric block, a pair of flexible prongs connected to said block and having free end portions projecting therefrom, wedge means disposed between said prong end portions, and an actuating rod threaded to said wedge means and swiveled in said block. 60

12. In a device of the character described, a plug fitting comprising a dielectric block, a pair of flexible prongs connected to said block and having 65 free end portions projecting therefrom, wedge means disposed between said prong end portions, and an actuating rod threaded to said wedge means and swiveled in said block, together with a fixture support mechanically connected with 70 said block, said prongs having electrical terminal means.
